UNITED STATES PATENT OFFICE.

JOHN H. ZIMMER, OF CHICAGO, ILLINOIS, ASSIGNOR TO EDMONDS-METZEL MANUFACTURING COMPANY, OF CHICAGO, ILLINOIS.

SAVINGS-BANK.

SPECIFICATION forming part of Letters Patent No. 718,184, dated January 13, 1903.

Application filed November 22, 1901. Serial No. 83,269. (No model.)

To all whom it may concern:

Be it known that I, JOHN H. ZIMMER, a citizen of the United States of America, and a resident of Chicago, in the county of Cook and State of Illinois, have invented certain new and useful Improvements in Savings-Banks, of which the following is a specification.

The main objects of my invention are to provide an improved savings-bank of simple, durable, and inexpensive structure, to provide an improved form of trap controlling the coin-slot, to provide for readily locking the cover to the body of the bank in different relative positions, and to avoid unnecessary obstructions in the interior of the body, and thus facilitate the removal of the contents when the bank has been opened.

It will be understood that many banking concerns now make it a practice to furnish small portable savings-banks to their depositors, the banking concerns retaining the keys of such portable banks and removing and counting the contents when brought for deposit. My bank has been designed particularly for such use with a view to saving time in removing the contents and relocking the bank and to providing a device suitable for this purpose which can be furnished at a comparatively low cost.

I accomplish the objects hereinbefore mentioned by the construction shown in the accompanying drawings, in which—

Figure 1 is a vertical longitudinal section of a device constructed according to my invention, the line of section being indicated by the line 1 1 in Fig. 2. Fig. 2 is a top plan of the same. Fig. 3 is a plan of the casing which supports the slot-closing mechanism of said device. Figs. 4 and 5 are respectively an elevation and a plan of one of the fingers employed in the said slot-closing mechanism. Figs. 6 and 7 are respectively an elevation and plan of the spring whereby the finger is actuated.

The device shown consists of a hollow steel receptacle having a cylindrical body 2. The bottom 3 is integral with the sides of said casing. The top is entirely open and has a counterbore 4, which is adapted to receive the cover 5. Said counterbore is of sufficient depth so that the cover will set into same with

its upper surface flush with the upper edge of the sides of the receptacle 2. An annular groove 6 is cut in the interior of the cylinder near its upper end, and the cover 5 is held in place by the two tongues 7 and 8, which are seated in the groove 6. The tongue 7 is movable, being a part of the lock 9, which is secured to the under side of the cover and provided with a keyhole 10, passing through said cover. The cover is further provided with a handle 11, with a circular hole 12 for the insertion of paper money, and with a coin-slot 13. On the under side of the cover 5 is a casing 14, which supports the slot-closing mechanism. The tongue 8 is preferably made integral with the casing 14, the whole being so constructed as to be readily stamped out of one sheet of metal. The casing is further provided with a slot 15, corresponding to the slot in the cover 5, and with lugs 16, whereby the casing is secured to said cover 5. The slot-closing mechanism consists of a plurality of fingers 17, pivoted to a shaft 18, which is secured within the casing 14 and parallel with the slot 13 of the cover. Each of the fingers 17 is provided with a pair of lugs 19, said lugs having therein the openings 20 for receiving the shaft 18. Each of the fingers 17 is also provided with a spring 21, which is wound around the shaft 18 and bears between the fingers 17 and the cover 5, tending to force said fingers into a closed position across the slot 13. Each of the fingers 17 also bears against a ball or roller 22. Said balls are confined within the casing 14 and adapted to hold the fingers 17 in a downwardly-inclined position, as shown in Fig. 1. The balls 22 further serve to prevent a coin inserted in the slot from being pressed by the finger 17 against the edges of both slots 13 and 15, thus reducing the friction and facilitating the insertion of the coin. A further use for the balls 22 is that they tend to roll across the slots and keep them closed when the fingers 17 are pressed downwardly. The fingers 17 have their free ends curved to fit the balls and pointed at 23 to prevent the withdrawal of a loop of paper or similar material if introduced for removing a coin.

The operation of this form of bank is as follows: When a coin is inserted in the slot 13, such of the fingers 17 as come in contact

with said coin are depressed to allow the passage of said coin, the balls 22 rolling slightly to facilitate such passage by the reduction of friction. The fingers 17 which are not in contact with the coin remain closed. The casing 14 supports the balls and protects the fingers from being injured by the contents of the bank. The position of the fingers insures that no coin can be shaken through the slot 15, so as to be removed from the bank. When it is desired to open the bank, by turning the key in the keyhole 10 the tongue 7 of the lock will be withdrawn from the groove 6, permitting the ready removal of the cover 5. It will be seen that with the removal of the cover the entire operating mechanism is removed, leaving the side walls of the body free from obstructions and avoiding the possibility of money being retained within the bank. When the bank is to be closed after the removal of the money, the cover may be returned, so that the tongue 8 enters the groove 6 at any point in its circumference, and the tongue 7 will then be let into the opposite part of said groove by means of the key. It will be seen that this construction avoids any necessity of carefully adjusting the cover to a particular position when returning same to the body of the receptacle, and thereby greatly lessens the labor of a cashier or teller, who handles many of such banks.

It will be seen that some of the details of the device shown may be altered without departing from the spirit of my invention. I therefore do not confine myself to such details except as hereinafter limited in the claims.

What I claim as my invention, and desire to secure by Letters Patent, is—

1. A savings-bank comprising a receptacle, open at one end and having a cylindrical interior free from obstructions to the outward passage of coins or paper money through said open end, and having an annular groove extending around its walls near said open end; a cover having therein a coin-slot; a suitable trap secured to said cover for preventing the outward passage of money through said slot; a pair of opposite locking-tongues secured to said cover and adapted to engage said groove at any opposite points along the groove; one of said tongues being movable into and out of locking position; and locking means for actuating said movable tongue.

2. A savings-bank, comprising a receptacle having a coin-slot through the wall of same, a casing secured to said wall and within said receptacle and having a corresponding slot, a spring-actuated finger seated in said casing and acting toward the slot in said wall, and a movable roller seated in said casing and adapted to limit the movement of said finger toward said slot.

65 3. A savings-bank, comprising a receptacle

having a coin-slot through the wall of same, a casing secured to said wall and within said receptacle and having a corresponding slot, a series of independent spring-actuated fingers seated in said casing and acting toward the slot in said wall, and a series of movable rollers seated in said casing and each limiting the movement of one of said fingers toward said slot.

4. A savings-bank, comprising a receptacle having a coin-slot through the wall of same, a casing secured to said wall and within said receptacle and having a corresponding slot, a series of independent spring-actuated fingers seated in said casing on one side of the slot in said wall and acting toward said slot, and a series of movable rollers seated in said casing on the opposite side of said slot and at the free ends of said fingers.

5. A savings-bank, comprising a receptacle having a coin-slot through the wall of same, a casing secured to said wall and within said receptacle and having a corresponding slot, a shaft in said casing extending along one side of said slot, a series of fingers 17 each having a pair of lugs 19 journaled on said shaft, springs 21 encircling said shaft between said lugs and each having a spring-arm bearing against the under side of the finger, and another spring-arm bearing against the inner surface of said wall and thereby holding said fingers normally across the slot in said wall.

6. A savings-bank, comprising a receptacle having a coin-slot through the wall of same; a casing secured to said wall within said receptacle and at said slot; a trap secured within said casing adapted to permit a coin to be passed inwardly through said slot from the outside of said receptacle, and to prevent the outward return of said coin through said slot; and a series of movable rollers in said casing interposed between the trap and said wall, limiting the movement of said trap toward the slot and adapted to bear against said coin and roll inwardly during the passage of said coin.

7. A savings-bank, comprising a receptacle having a coin-slot through the wall of same, a casing secured to said wall within said receptacle and having a corresponding slot, a series of independent spring-actuated fingers seated in said casing on one side of the slot in said wall and acting toward said slot, and a series of movable balls seated in said casing on the opposite side of said slot and at the free ends of said fingers, the free ends of said fingers being curved to fit said balls and provided with points for the purpose specified.

Signed at Chicago this 6th day of November, 1901.

JOHN H. ZIMMER.
